CLAIM

The ornamental design for a model vehicle body assembly as shown and described.

DESCRIPTION

FIG. 1 is an upper, left, front perspective view of a model vehicle body assembly showing our new design;

FIG. 2 is an upper, right, rear perspective view thereof;

FIG. 3 is a lower, left, rear perspective view thereof;

FIG. 4 is a lower, right, front perspective view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is an upper plan view thereof; and,

FIG. 10 is a lower plan view of the model vehicle body assembly.

In the drawings, the broken lines illustrate portions of the model vehicle body assembly that form no part of the claimed design.
